UNITED STATES PATENT OFFICE.

FAIRBANK BARNES STOCKDALE, OF BROOKLYN, NEW YORK, AND HOBART ARTHUR SIMPSON, OF OCEAN GROVE, NEW JERSEY.

SELF-STARTER.

1,386,139.

Specification of Letters Patent.

Patented Aug. 2, 1921.

Application filed August 20, 1918. Serial No. 250,721.

To all whom it may concern:

Be it known that we, FAIRBANK BARNES STOCKDALE and HOBART ARTHUR SIMPSON, citizens of the United States, residing at 5 Brooklyn, New York, and Ocean Grove, New Jersey, respectively, have invented certain new and useful Improvements in Self-Starters, of which the following is a clear, full, and exact description.

10 This invention relates to power-storing mechanism of the spring type, and particularly to power-storing mechanism of the type adapted to be employed as starting means for internal combustion engines.

15 An object of the invention is to provide power-storing mechanism of the spring type which, when associated with a suitable source of power, such as an internal combustion motor, as a starting means for said 20 motor, will be automatically maintained in condition for use without attention from the operator, and will be immediately and automatically restored to such condition when it has effected the starting operation.

25 The invention herein shown is an improvement on those shown in our Patent 1,311,190, dated July 29, 1919, of which the present application is a continuation as to common subject matter.

30 An important feature of the invention is the provision in power-storing mechanism of the spring type in which means controlled by the shape of the spring automatically stops the tensioning operation when a predetermined tension has been reached, and again starts the tensioning operation when the tension falls below the predetermined maximum, of means preventing the operation of such automatic means when the

35 spring is delivering power. Another important feature of the invention is the arrangement at one end of the power-storing spring of a single power transmitting means and separate clutches for connecting said power transmitting means to said spring for tensioning said spring and for delivering the power of said spring to said power transmitting means.

40 Another important feature of the invention is the provision of a surface of considerable extent against which the spring acts on being tensioned and by which the power delivering clutch is opened.

Another important feature of the invention resides in the nesting of the several 55 parts so that compactness is secured.

Another important feature of the invention resides in the tapering form of the power spring whereby evenness of action is secured.

60 Another important feature is the provision of a thrust bearing in coöperation with the power storing and power delivering clutches, such that there is no binding between the parts which are required to rotate relatively to one another.

Another important feature relates to the form of reduction gearing used between the motor and the power spring winding means.

65 Other important features and objects of 70 the invention will appear from the following description and claims when considered in connection with the accompanying drawings, in which—

75 Figure 1 is a longitudinal sectional view of the power storing and motor starting means of the present invention;

Fig. 2 is a view in which the casing is shown in section but the interior parts are shown in full. In this view some of the 80 parts appearing in Fig. 1 are necessarily covered;

Fig. 3 is a side elevation of a portion of the right-hand end of the device and showing the clutches, which deliver power from 85 the starting spring to the motor, in normal position;

Fig. 4 shows the same parts as Fig. 3, but moved to start the motor;

Fig. 5 shows the same parts while the 90 power spring is being rewound by the motor;

Fig. 6 is an elevation of the rewinding controllers looking in the direction of the arrow, Fig. 1;

95 Fig. 7 is a view, part in section and part in elevation, of the rear portion of the device and showing the position of the parts concerned in the rewinding of the power spring, these parts having the positions 100 shown when the starting clutch shown in Fig. 4 is engaged to start the motor but with the parts set for preventing rewinding of the power spring;

105 Fig. 8 is a view of the same parts moved to cause closing of the rewinding clutch

shown closed in Fig. 5. Rewinding of the power spring takes place with the parts in the Fig. 8 positions;

Fig. 9 shows some of the same parts as shown in Figs. 7 and 8, after the power spring has been rewound;

Fig. 10 is a rear elevation, and part sectional view of the holding ratchet and its pawls, the view being taken on about the line A—B, Fig. 1;

Fig. 11 is a part elevation and part sectional view of the right-hand portion of the device as shown in Fig. 1, but showing the application of our improved reduction gear-
ing thereto;

Fig. 12 is an end elevation of said gear-
ing;

Fig. 13 is an enlarged view showing the shape of the teeth on the clutch members 52 and 64, and the clutch members 44 and 90;

Fig. 14 is an enlarged view of the thrust bearing shown at the right central portion of Fig. 1; and

Fig. 15 is an enlarged view of the teeth of the clutch members 50 and 56.

Fig. 16 is a longitudinal section of a portion of the structure shown in Fig. 1 and on an enlarged scale;

Fig. 17 is a similar view but with the parts in operated positions; and

Fig. 18 is a front elevational view of the levers 158, the shafts 14 and 80 being shown in cross section.

The illustrated mechanism comprises a cylindrical casing 2 in which are fixed bearings 4 and 6 for the spring-tensioning and power-delivering mechanisms, the spring 8 in which the power is stored being located between these bearings and having its respective ends connected to circumferentially grooved spring coil holders 10 and 12. The coil holder 10 is keyed upon a shaft 14 supported in ball bearings 16 in the bearing member 6, and the coil holder 12 is carried upon a sleeve 18, splined upon a second sleeve 19, upon the shaft 14, said sleeve 18 being surrounded by a bearing cone 20 traveling upon ball bearings 22 in the bearing member 4. The coil holder 12 is clamped to the sleeve 18 and cone 20 by a set nut 24 threaded upon the sleeve 18, said nut serving to force the hub of the coil holder 12 against the cone 20 and in turn to force the cone 20 against the flange 26 upon the sleeve 18. The cone 20, sleeve 18 and sleeve 19 together provide a second bearing support for the shaft 14 in the bearing member 4.

At the right-hand end of the casing 2 in Figs. 1 to 5 inclusive, is shown a support 28 for any suitable power-transmitting means by which the stored power of the spring may be transmitted to the motor and by which the power of the motor may be utilized to tension the spring, the illustrated means comprising a sprocket wheel 30 which

is connected by the usual sprocket chain to the motor crank shaft. The support 28, which has the sprocket-carrying hub 36, fits within the right-hand end of the casing and has a rearwardly extending hub 38, Fig. 1, 70 carried upon bearings 40 upon the shaft 14, these bearings being confined between set nuts 42 upon the right-hand end of the shaft 14 and a clutch member 44 carried by the hub 38. The hub 38 may also carry a spring 75 plate 46 by which felt or other suitable washers 48 are pressed against the inner face of the support 28 at its outer edge, in order to seal the casing 2 against dust and to prevent the loss of the lubricant by which the 80 parts within the casing are lubricated.

The clutch member 44, by means to be presently described, serves to transmit the power from the sprocket wheel 30, when said sprocket is being turned under power of the 85 motor.

In addition to the clutch member 44, the hub 38 of the support 28, also carries a clutch member 50, which is concentric with and projects beyond the clutch member 44, 90 each of these clutch members being made in the form of crown wheels having ratchet teeth. For reasons which will be explained hereinafter, the shape of the teeth of the clutch member 50 differs somewhat from 95 those of the member 44. Coöperating with the clutch member 50 is a second toothed clutch member 52, which is pinned upon the sleeve 19, the sleeve 19 having a flange 54 against which the web of the clutch member 52 100 abuts. The clutch member 52 has ratchet teeth 56, shaped to mesh with the ratchet teeth 58, of the clutch member 50, and also has upon the other edge of its rim ratchet teeth 60, adapted to mesh with corresponding ratchet teeth 62, upon a locking plate 64 attached to the bearing support 4.

The clutch member 52 is normally held in such position that the teeth 60 engage the teeth 62 of the locking plate 64, by means of 110 a spring 66 surrounding the sleeve 19 and bearing at one end against the sleeve 18 and at its other end against a collar 68 threaded upon the sleeve 19. The space between the teeth 58 of the clutch member 50 and the teeth 62 of the locking plate 64 is not sufficient to permit the complete disengagement of the clutch member 52 from the locking plate 64 before it engages the clutch member 50 or vice versa.

The means for effecting the movement of the clutch member 52 into clutching relation to the clutch member 50 comprise a thrust bearing made up of disks 70 and 72 between which are located ball bearings 74, this 125 thrust bearing resting against the end of the sleeve 19, and being engaged by a cross-piece 76 projecting to either side of the shaft 14 and traveling in a slot 78 in said shaft, Fig. 4, said cross-piece being connected to a rod 130

80 movable within the shaft 14. At its outer end the rod 80 is threaded and carries a member 82, engaged by a lock nut 84. A lever 86 pivoted at 88 to some stationary part, bears at its lower end against the member 82. Said lever 86 is suitably connected to be conveniently operated from the dash board of the motor vehicle, either by hand or by a foot lever, but preferably by the latter and when rocked in the direction of the arrow, Fig. 1, moves the sleeve 19 upon the shaft 14, against the tension of the spring 66 and thereby carries the clutch member 52 into engagement with the clutch member 50. When the motor starts it gives a kick to the clutch member 50, which acts to cam the clutch member 52 to the left, to bring its teeth 60 into engagement with the locking teeth 62. It will be noted that the member 52 is rotating at this time and if the teeth 60 and 62 were pointed, their ends would clash, causing stripping of the teeth. To prevent this the teeth 60 and 62 are made flat on their ends as shown in Fig. 13. On the other hand, the teeth 56 and 58 are made pointed because when the parts are at normal the members 50 and 52 may not be in perfect meshing relation and when 52 is moved toward 50 it may have to cam said member 50 a distance of a portion of a tooth before perfect meshing takes place. The pointed teeth permit engagement of the two members 50 and 52 in any position which they may occupy relatively to one another. In order to enable the member 50 to be easily turned by the member 52 sliding into engagement therewith, the teeth of one of these members are shaped as shown in Fig. 15, wherein the angle formed at the point of the teeth of one set is different from that of the teeth of the other set.

Coöperating with the clutch member 44 is a second clutch member 90 of similar construction, each of these clutch members having coöperating ratchet teeth similar to the ratchet teeth 60 and 62 hereinabove described, the clutch member 90 being arranged to slide upon the shaft 14 into and out of engagement with the clutch member 44. This movement of the clutch member 90 is preferably effected automatically in accordance with the tension of the spring 8, the clutch member 90 being so connected to the shaft 14 that it turns said shaft to tension the end of the spring remote from the sprocket wheel 30.

The illustrated means for automatically controlling the tensioning of the spring comprises means operated by the change in shape of the spring as it is tensioned to automatically disconnect the tensioning means and to again connect said tensioning means when the spring tension falls below a predetermined point. This mechanism is located within the spring coil and comprises

a two-part cylinder 92, which is movable by the spring 8 from an open condition such as shown in Fig. 1, when the spring 8 is not completely tensioned to a closed cylindrical condition such as shown in Fig. 9 when the spring is tensioned to the desired amount. Means are provided which tend to maintain the two-part cylinder in its open condition, the illustrated means comprising a pair of rewinding controllers 94, mounted for sliding movement in guides 96, carried by, or formed on the coil holder 10. Mounted for adjustment in a radial slot in each controller is a finger 98. These fingers are held in adjusted position, each by a set screw 100, and are adapted to be engaged by the walls of the two-part cylinder so as to slide the controllers toward the center of the shaft 14 as the spring 8 is being retensioned. The adjustment of the fingers provides means for determining how much the spring shall unwind before it acts on the controllers to bring mechanism into play for rewinding itself, such rewinding being brought about when the clutch member 90 engages the clutch member 44, thereby permitting power to be transmitted to the shaft 14 (the clutch member 90 being secured to shaft 14 but slidable thereon) and thence to the coil holder 10. To throw the two-part cylinder 92 to its open position, springs 91 are provided, such springs being mounted on pins 93 in the coil holder 10 and engaging the shoulders of the controllers 94, each spring being tensioned over a pin 95 as shown in Fig. 6. Clutch member 90 is engaged by a cross-piece 102 secured to a tubular member 104, which member occupies the center of shaft 14, the cross-piece 102 passing through slots in the shaft 14 and through slots in the hub of the clutch member 90. Adjacent the controllers 94, the member 104 is slotted as shown in Figs. 1, 7, 8 and 9. The controllers are straight on the front edges but at the rear are formed with cam edges for engagement with the wall of the slot in the member 104 to move said member to the left when the two-part cylinder is moved by the tensioning of the spring 8 to the position of Fig. 9. A spring 110 seated against a screw 112, in the end shaft 14, tends to move the tubular member 104 to the right and therefore to close the clutch 90.

With the spring 8, fully tensioned, as in Fig. 9, if it is desired to deliver the power of the spring, the clutch member 52 may be moved into engagement with the clutch member 50 by the manually operated means hereinabove described, such movement carrying the teeth 60 out of engagement with the teeth 62 of the locking plate 64, thereby permitting the spring to turn the sprocket wheel 30 and whatever is connected with said sprocket wheel. As soon as the spring begins to deliver its power, its tension of

course becomes less, and were it not for the important feature of the invention now to be described, as soon as the tension of the spring should fall below a predetermined amount, the parts would assume the position shown in Fig. 8 because just as soon as spring 8 begins to lose tension it becomes larger, thereby permitting the two-part cylinder to expand under the action of the 10 springs 91 to the position of Fig. 1 and the spring 110 would at once act to move the tubular member 104 to the right, Fig. 8, and cause the clutch 90 to close.

To prevent the closing of the clutch 90 15 when the spring 8 is delivering power and until the motor has started, the novel means now to be described, are provided. I have shown two forms of these means and will first describe that form illustrated in Figs. 20 7 and 8. Mounted for movement toward and from the center of the shaft 14 is a latch member 114 which is held seated in a recess in the shaft by spring 116. The latch member passes through a slot 117 in the 25 tubular member 104, and a shoulder 118 on the latch member normally bears against the rear wall of the slot, thus holding the tubular member against movement to the right under action of the spring 110 even though 30 the controllers 108 have been spread apart as shown in Fig. 7. The spring 8 delivers its power as long as the clutch members 50 and 52 are closed, and these, it will be remembered, are moved to closed position by 35 the manual movement of the lever 86 acting through the rod 80 and sleeve 19. In the form of device shown in Figs. 7 and 8, the rod 80 is conical at its end 122 and when said rod 80 is moved to the left on opening 40 of the clutch members 50 and 52, the surface 122 engages the latch member 114 and moves it from the position of Fig. 7 to the position of Fig. 8. Spring 110 immediately acts to throw rightwardly the tubular member 104, 45 thereby closing the clutch members 90 and 44 so that power from the engine, delivered to the sprocket wheel 30 will be transmitted through the shaft 14 to the coil holder 10 and wind up spring 8. As soon as this becomes 50 fully wound, it closes the controllers 94 and they in turn pull the tubular member 104 back to the position of Fig. 9, the latch 114 at this time occupying the position shown in Fig. 8. It remains in this position 55 until the lever 86 is again moved to throw in the clutch members 50 and 52, when it is released from the cam 122 and moves up to the position of Fig. 7 to prevent any movement of the tubular member 104, to the 60 right to close the clutches 44 and 90. In this form of the device the spring 66 is not strong enough to open the clutches 44 and 90 should the lever 86 be released without the motor starting, the starting of the 65 motor being relied upon to give a kick to the

clutch member 50 to separate the clutch member 52 therefrom by the camming action of its teeth.

In the preferred form of the device, which is that form shown in Figs. 1, 16, 17 and 18, 70 we have shown positively acting means under the control of the lever 86, for preventing the clutches 44 and 90 from being in engagement when the clutch members 50 and 52 are in engagement. To accomplish 75 this, we pivot two levers 158, at 160, in the side walls of slots cut into the shaft 14. These levers are mounted in such relation to the clutch member 90, that when moved from the position shown in Fig. 16, to that 80 of Fig. 17, the clutch member 90 is held in its normal position during the time the spring 8 is delivering power. To move the levers 158, a disk 162 is made fast to the rod 80 so that the levers are under positive 85 control of said rod. The levers 158 cross each other at their ends and are so shaped as to provide a passageway for the rod 80, as shown in Fig. 18. The form of device above described is useful in case the motor 90 does not start upon the closing of the 95 clutches 50 and 52 due to any cause, such for instance, as the operator forgetting to have the ignition circuit turned on. In such an event, if the clutches 50 and 52 could not be disconnected, the spring 8 would continue to unwind. But with this mechanism under positive control of the lever 86, just as soon as said lever is released the rod 80 moves to the left under action of spring 66, which is made 100 strong enough in this form of device, to open the clutches 50 and 52, even though the motor does not start. Thus with the clutches 50 and 52 separated, the spring 8 no longer delivers power, and if it has unwound sufficiently to permit the controllers 94 to move apart, allowing the spring 110 to act, the clutch member 90 will be thereby brought into engagement with the clutch member 44. This, however, will do no harm because just 105 as soon as the lever 86 is again operated, the clutch members 44 and 90 will be positively separated by the action of the levers 158.

It will be noted that in the operation of the automatic mechanism for disconnecting 115 the clutch member 90 from the clutch member 44, when the spring is approaching its predetermined tension, the resistance to the separating movement of the clutch members, due to the pressure of the tensioned spring 120 8, will cause a slight accumulation of power just before the separation takes place, thus moving them into such position, as shown in Fig. 4 of the drawings, that when the separation does take place that there will be no 125 danger of the accidental engagement of the teeth while the clutch member 44 is being driven by the motor.

In order to provide for as long a spring 8 as possible and at the same time avoid in- 130

creasing the length of the whole device beyond convenient limits, the bearing 4 is nested within the coil holder 12, as shown in Fig. 1, and the bearings 20, clutch members 50, 52, 44 and 90 are nested within the bearing 4.

In order to take the thrust of the sleeves 18 and 19, a thrust bearing is provided and this bearing is constructed in a particular manner so as to permit ease of rotation of the hub 38 and independent rotation of the shaft 14 when the clutch members 44 and 90 are in engagement. This bearing differs from those of the usual type in that there is provided a flanged disk member 128 which bears against the outer race member of the bearing 40, as shown in Fig. 14, instead of the inner race member. When the bearing is adjusted, pressure, caused by the tightening of the set nuts 42, is transmitted through the balls of the bearing to the flanged disk 128 and thence to the outside race member of the bearing 40. The portions 132 of the flanged disk 128 do not touch the inner race member of the bearing 40. When the hub 38 rotates under the driving action of the motor it carries with it the outer race which rotates on the balls 41. At this time the clutch members 44 and 90 are in engagement so that the shaft 14 is also being rotated together with the lock nuts 42 and bearing piece 134. The pressure of the bearing piece 134 against the balls 136 is transmitted through the bearing disk 138 to the member 128 and thence to the outer race member of the bearing 40 as already set forth and there is therefore, no binding of either of the balls 41 or balls 136 in their bearings. If, however, the bearing ring 138 transmitted the pressure of the balls 136 to the inner race of the bearing 40 there would be a binding because the inner race moves relatively to the bearing disk 138 and in adjustment of the bearing would act to clamp said disk 138 against the inner race of the bearing 40.

In Fig. 1, the sprocket 30 is directly connected to the member 38 to which is connected the clutch member 44. With this construction the power of the spring is directly applied to start the motor and also the full load of the spring 8 is thrown upon the engine during rewinding. While this arrangement gives satisfaction in practice, it may be, nevertheless, desirable in some cases to relieve the motor of the entire force of the spring 8 as the motor starts and to accomplish this, we have provided reduction gearings between sprocket 30 and the hub 38, said reduction gearing being shown in Figs. 11 and 12.

Referring to Fig. 11, the sprocket 30 is keyed to a stub-shaft 140 supported by ball-bearings carried by the member 38 and by the supporting member 142. Formed in-

tegral with or rigidly connected to the stub-shaft 140 is a central pinion 144. Also rigid with the stub-shaft 140 is a ratchet 146 engaged by three pawls, 148, three pawls being used to provide a balanced structure. The direction of movement of the sprocket 30 and hence the stub-shaft 140, is clockwise and, therefore, the teeth of the ratchet 146 are in a direction to permit clockwise movement of the ratchet, but the pawls 148 prevent anti-clockwise movement of said ratchet. It will be recalled that when the spring 8 is delivering its power, the hub 38 is rotated in a clockwise direction. Since the pawls 148 are carried directly by the hub 38, said pawls will act to drive the ratchet 146 and hence the stub-shaft 140 and sprocket wheel keyed thereto, all in a clockwise direction, thereby delivering power to start the motor. When, however, the motor has started and power is being delivered by the motor to the sprocket 30 and the connection from the spring 8 to the hub 38 is broken, the ratchet 146 slips under the pawls 148. The hub 38 at this time, however, is being driven in a clockwise direction and retensioning of the spring 8 is accomplished by an indirect connection to the hub 38 from the central gear 144. Meshing with the central gear 144 are three gears 150 and meshing with each of the gears 150 is a gear 152. Gears 152 mesh with internal teeth 154 carried by the hub 38. Gears 152 mesh with gears 150, but do not mesh with the central gear 144. The gears 150 and the gears 152 are supported by the stud-shafts 151 carried by the member 142. When therefore, the shaft 140 and gear 144 is rotated clockwise, Fig. 12, clockwise motion will also be transmitted to the hub 38 through gears 150 and 152, the number of teeth on gears being such as to transmit the movement of the gear 144 to the hub 38 in a reduced ratio.

When the spring 8 is in an untensioned condition and is wound by rotation of the coil holder 10 the coils to the extreme right are first reduced in size due to the winding of the spring. These right-hand coils, it will be noted, include within them the sleeved portion of the coil holder 12. To prevent any binding action of the spring as it is being wound, it is so shaped that there is a slight taper from the right-hand toward the left-hand end, the right-hand end in normal untensioned condition being slightly larger than the left-hand end. This taper is so proportioned relative to the size of the spring, the number of coils and the degree to which the spring is to be tensioned, that when the spring is in its tensioned condition the sides thereof, are substantially parallel.

The coil holder 10 has secured to it the ratchet 124, engaged by three pawls 126, Fig. 10, to hold the spring while being wound.

To prevent the pins 98 from being displaced, longitudinal guides 156 are provided and are secured to the inside of the two-part cylinder.

5 It will be noted that, in the illustrated structure, all connections and all means for storing power and for delivering power are arranged in radial symmetry about the axis of the spring, whereby all forces in the 10 structure are balanced and there is no tendency to binding or lateral distortion with the attendant loss of power and the resultant reduction both of the efficiency and of the life of the structure. By the improved 15 construction of the present invention, a very efficient self-starting means, for use in automobiles, has been provided, this means being so compact that it can readily be installed in automobiles of ordinary design, 20 without modification of the structure of the machine, and yet being so powerful that it will turn the crank shaft of the engine a sufficient number of times to effect starting under ordinary conditions. In fact, this 25 invention, as actually embodied in structures of commercial design, has a sufficient reserve of stored power so that it will effect the starting of the automobile motor even in cold weather and under other particularly 30 difficult conditions.

What we claim as new is:—

1. In a power storing mechanism, in combination, a rotatable member, a power storing spring, automatically releasable winding 35 means at one end of said spring operable from said rotatable member, manually controlled means for causing the other end of said wound up spring to deliver its torque to said rotatable member comprising a member carried by said other end of the spring, a member operatively connected with the rotatable member, and means for moving one of said members into and out of engagement with the other.

4. 2. In a power storing mechanism, in combination, a rotatable member, a power storing spring, winding means at one end of said spring operable from said rotatable member and acting automatically to maintain said spring in wound up condition, 50 manually controlled means for causing the other end of said wound up spring to deliver its torque to said rotatable member, comprising a member carried by said other end of the spring, a member operatively connected with the rotatable member, and means for moving one of said members into and out of engagement with the other.

3. In a power storing mechanism, in combination, a rotatable member, a shaft in operative relation to said member and having mounted thereon a power storing spring, winding means for said spring operable from said rotatable member and acting automatically to maintain said spring in wound 55

up condition, and manually controlled means for causing said wound up spring to deliver its torque to said rotatable member comprising a driving member connected with said spring, a stationary holding member and a drivable member connected with said rotatable member, said driving and drivable members mounted on said shaft. 70

4. In a power storing mechanism, in combination, a rotatable member, a power storing spring, winding means at one end of said spring operable from said rotatable member, means for causing the other end of said wound up spring to deliver its torque to said rotatable member comprising a driving member connected with said spring, a stationary holding member normally in engagement with said driving member, a drivable member connected with said rotatable member, and manually operated means for engaging said driving and drivable members and disengaging said driving and holding members. 75 80

5. In a power storing mechanism, a shaft, a power storing spring surrounding said shaft, a casing surrounding said shaft and spring, a winding gear member rotatably mounted on said casing and said shaft, a clutch for connecting said winding gear member and said spring, means for controlling said clutch, the operation of said means depending upon the degree of compression of said spring, a driving member connected with said spring, locking means for normally preventing the rotation of said driving member, a drivable member rotatably mounted on said casing and shaft, and means for engaging said driving and drivable members and disengaging said locking means. 90 95 100

6. In a power storing mechanism, a casing, rotatable members mounted on opposite ends of said casing, a spring in said casing, automatic means in said casing for connecting one end of said spring to one of said 110 rotatable members for winding said spring, and manually controlled means for connecting the other end of said spring with the other rotatable member for driving the same. 115

7. In a power storing mechanism, a spring to be tensioned, means for tensioning said spring, means tending constantly to maintain an operative connection between said tensioning means and said spring and held 120 against said tendency by the changed shape of the spring when the spring has reached a predetermined tension, and other means rendered operative when said spring is actuated to deliver power for preventing the connection of said tensioning means to said spring while said spring is delivering power. 125

8. In apparatus of the class described, the combination with a spring to be tensioned, of power transmitting means through which 130

- said spring power may be utilized and through which said spring may be tensioned, of means arranged in radial symmetry about the axis of said spring for connecting said power transmitting means to said spring for the respective purposes, said means comprising means tending at all times to restore or to maintain said tensioning connection and held against said tendency by the changed shape of the spring when the spring has reached a predetermined tension, and other means for preventing the restoration of said tensioning connection when said spring is connected to said power-transmitting means to deliver its power thereto. 5
9. In apparatus of the class described, a spring to be tensioned, means for tensioning said spring, means extending within said spring, arranged to operate equally upon opposite sides of the axis thereof and controlled by the change in the inside shape of the spring under different degrees of tension for automatically connecting said tensioning means to said spring and disconnecting it therefrom when the spring tension respectively falls below or reaches a predetermined point, mechanism by which the stored power of said spring may be utilized, actuating means for said mechanism, and means 20 brought into operation by the actuation of said mechanism for preventing said aforementioned connection when the spring is delivering power. 25
10. In apparatus of the class described, the combination with a helical spring to be tensioned, power-transmitting means adapted to be connected to one end of said spring to tension said spring and to the other end of said spring to receive the stored power 30 therefrom, manually controlled means for effecting the power delivering connection, automatic means extending within the spring helix and controlled by the change in dimensions of said helix for effecting the spring 35 tensioning connection, and means associated with said manually controlled means for rendering said automatic means inoperative when the spring is delivering power, each of said means being arranged to operate symmetrically with respect to the axis of said spring. 40
11. In apparatus of the class described, a spring to be tensioned, power-transmitting means normally disconnected from said spring but adapted to be connected to said spring to tension it and also adapted to be connected to said spring to receive the stored power therefrom, automatic means controlled by the fall of the spring tension below a predetermined point for effecting the 45 first mentioned connection, manually controlled means for effecting the second mentioned connection and comprising a member movable from spring locking position into spring connecting relation to said power- 50
- transmitting means, and means rendered operative by the actuation of said manually controlled means for preventing said automatic connection when the spring is delivering power. 55
12. In apparatus of the class described, a helical spring to be tensioned, power-transmitting means normally disconnected from said spring but adapted to be connected to one end of said spring to tension said spring 60 and adapted to be connected to the other end of said spring to receive power therefrom, means comprising mechanism operating within said spring symmetrically with respect to the axis thereof and controlled by the change in shape of the spring for automatically effecting said first mentioned connection when the spring tension falls below a predetermined point, and manually controlled means also operating symmetrically with respect to the axis of said spring for effecting the second mentioned connection, said last mentioned means comprising means extending within said spring for rendering said automatic means inoperative. 65
13. In apparatus of the class described, a helical spring to be tensioned, a clutch member connected to one end of said spring and movable between a spring locking position and a power-transmitting position, stationary and movable clutch members respectively coöperating with said first mentioned clutch member for effecting the locking of the spring and the transmission of its power and between which said first mentioned clutch member is movable, a second clutch member concentric with said first-mentioned clutch member and having a connection to the other end of said spring, and a coöperating clutch member connected to said power-transmitting clutch member, said clutch members connected to the respective spring ends being independently movable into clutching relation to the coöperating clutch members. 70
14. In apparatus of the class described, the combination with a helical spring to be tensioned, of power-transmitting means comprising concentric clutch members, other clutch members coöperating with the respective concentric clutch members and one of which is connected to one end of said spring and the other of which is connected to the other end of said spring, means for independently effecting relative movement of the coöperating clutch members into clutching relation, and locking means for holding the respective spring ends tensioned when neither of said pairs of coöperating clutch members is in clutching engagement. 75
15. In apparatus of the class described, the combination with a helical spring to be tensioned, power-transmitting means located at one end of said spring and comprising concentric connected clutch members, in- 80

- dependent clutch members coöperating with said concentric clutch members and one of which is connected to the adjacent end of said spring and the other of which is connected to the remote end, said last mentioned connection comprising a shaft extending through said spring, a ratchet lock at each end of said spring, a connection between one of said ratchet locks and one of said 10 clutch members, whereby movement of said clutch member into clutching position releases said lock and permits the delivery of the stored power of the spring, a sliding key connection between the other clutch and the 15 other lock, permitting movement of said clutch member into clutching position to tension said spring and the locking of said spring in tensioned position, and means for automatically effecting the last mentioned clutching operation when the spring 20 tension falls below a predetermined point.
16. In apparatus of the class described, the combination with a helical spring for storing power, of power-transmitting means located at one end of said spring, means movable along the axis of said spring for connecting said power-transmitting means with one end of said spring to tension said spring, other means movable 25 along the axis of said spring for connecting said power-transmitting means with the other end of said spring to receive the stored power, and means located within said spring and controlled by its change in 30 shape under different degrees of tension for automatically making and breaking said first mentioned connection according as the spring tension falls below or reaches a predetermined maximum.
- 35 17. In apparatus of the class described, the combination with a helical spring for storing power, of power-transmitting means located at one end of said spring, a clutch member connected with one end of said 40 spring and movable between a position in which it locks said spring under tension and a position in which it connects said spring to said power-transmitting means to deliver the stored power thereto,
- 45 50 and a second clutch member connected with the other end of said spring and adapted to be moved into and out of clutching relation to said power-transmitting means, each of said clutch members being movable along 55 the axis of said spring and said power-transmitting means being normally disconnected from said spring.
- 55 18. In apparatus of the class described, a cylindrical casing, a helical spring for 60 storing power confined within said casing, power-transmitting means at one end of said casing, said means being normally disconnected from said spring, clutches movable along the axis of said spring for connecting 65 said power-transmitting means with one end of said spring to tension said spring, and for connecting said means with the other end of said spring to receive the stored power therefrom, and means within said casing and operated by a change in shape of said spring 70 under changes in tension for automatically effecting the movement of one of said clutches.
19. In apparatus of the class described, a helical spring for storing power, power 75 transmitting means located at one end of said spring, and separate clutches also located at said end of said spring for connecting said power-transmitting means to one end of said spring to tension said spring, 80 and to the other end of said spring for receiving stored power therefrom, and means controlled by changes in the diameter of the spring coil due to the changes in tension for automatically operating one of said 85 clutches.
20. In apparatus of the class described, a helical spring for storing power, normally freely rotatable power transmission means at one end of said spring, separate clutches 90 movable along the axis of said spring into and out of engagement with said power transmitting means for connecting said means to said spring to tension said spring and to receive the stored power therefrom, 95 and means coöperating with one of said clutches, when said clutch is out of operative relation to said power-transmitting means, for holding said spring under tension.
21. In apparatus of the class described, 100 a cylindrical casing, a helical spring for storing power confined within said casing, bearing supports between which said spring is located, locks for holding said spring in tensioned condition, means, having bearings 105 in said supports, for tensioning said spring and for delivering the stored power of said spring, a power transmitting member in one end of said casing normally disconnected from said means, and clutches for effecting independent connections of said power-transmitting member and said means for the 110 purposes aforementioned.
22. In apparatus of the class described, a cylindrical casing, a helical spring for storing power confined within said casing, power transmitting means at one end of said casing, clutches movable along the axis of said spring for connecting said power transmitting means with one end of said 115 spring to tension said spring and for connecting said means with the other end of said spring to receive the stored power therefrom, and means coaxial with and movable along the axis of said power transmitting means for effecting the movement of said clutches.
23. In apparatus of the class described, a cylindrical casing, a helical spring for storing power confined within said casing, 120
- 125
- 130

- power-transmitting means at one end of said casing, clutches movable along the axis of said spring for connecting said power-transmitting means with one end of said 5 spring to tension said spring and for connecting said means with the other end of said spring to receive the stored power therefrom, and means coaxial with and movable along the axis of said power-transmitting means for effecting the movement 10 of said clutches, one of said clutch moving means being arranged for manual operation from the outside of said casing and the other being automatically operated from the inside of said casing.
24. In a power storing mechanism, a shaft, a power storing spring surrounding said shaft, a rotatable member for winding said spring, a clutch between said spring 20 and said rotatable member, means for controlling said clutch, said means mounted on said shaft and sliding transversely thereof as said spring expands or contracts, and connections between said means and said 25 clutch whereby the clutch is operated to connect the spring and rotatable member when the spring is unwound and to disconnect the spring and rotatable member when the spring is fully wound.
30. 25. In a spring starting device, the combination with a helical spring, of means connected to one end of said spring for tensioning the same, and means connected to the other end of said spring for receiving 35 power from the spring, said spring when in untensioned condition being tapered toward its tension receiving end.
26. In a spring starting device, the combination with a helical spring, of means 40 connected to one end of said spring for tensioning the same, and means connected to the other end of said spring for receiving power from the spring, said spring when in normal tensioned condition having its sides 45 substantially parallel but built to have a taper toward its tension receiving end when in untensioned condition.
27. In a spring starting device for an internal combustion motor, the combination 50 with a helical spring for delivering power to the motor, of manual means for connecting one end of said spring to the motor to start the same, means to connect the motor to the other end of said spring to rewind 55 the spring and means rendered effective when said manual means is operated for preventing the rewinding connections from becoming effective while said spring is delivering power to the motor.
60. 28. In a spring starting device for an internal combustion motor, the combination with a helical spring for delivering power to the motor, of means for connecting one end of said spring to the motor to start the 65 same, spring actuated means tending to connect said motor and the other end of said spring to rewind the same under the action of the motor, means controlled by the unwinding of the power spring for permitting said spring actuated means to act, and 70 means for preventing said action while the other end of the power spring is connected to said motor to deliver power to the same.
29. In a spring starting device for an internal combustion motor, the combination 75 with a helical spring for delivering power to the motor, of means for connecting one end of said spring to the motor to start the same, spring actuated means tending to connect said motor and the other end of said 80 spring to rewind the same under the action of the motor, controllers moved by said power spring as the same approaches tensioned condition for disconnecting said motor and power spring, thereby tensioning 85 said spring actuated means, said controllers releasing said spring actuated means as said power spring loses tension.
30. In a spring starting device for an internal combustion motor, the combination 90 with a helical spring for delivering power to the motor, of means for connecting one end of said spring to the motor to start the same, spring actuated means tending to connect said motor and the other end of said 95 spring to rewind the same under the action of the motor, controllers moved by said power spring as the same approaches tensioned condition for disconnecting said motor and power spring, thereby tensioning 100 said spring actuated means, said controllers releasing said spring actuated means as said power spring loses tension.
31. In a spring starting device for an internal combustion motor, the combination 105 with a power spring for delivering power to the motor, of means for connecting one end of said spring to said motor to start the same, a winding clutch between the other end of said spring and motor whereby said 110 motor may rewind said spring, said clutch being normally open when the other end of said spring is connected to said motor, means controlled by the power spring as it loses tension tending to close said clutch, and means for preventing the closing of said clutch while the driving end of said spring is connected to said motor.
32. In a spring starting device for an internal combustion motor, the combination 115 with a power spring for delivering power to the motor, clutching means for connecting one end of said spring to the motor to start the same, manual means for moving said clutching means to operative position,

a second clutching means to connect said motor to the other end of said spring to rewind the same, spring actuated means controlled from said power spring as the same is unwound for acting on said rewinding clutching means, and means operated by said manual means for positively acting on said rewinding clutching means to hold the same in unclutched position against the action of said spring actuated means.

33. In a spring starting device for an internal combustion motor, the combination with a helical spring for delivering power to the motor, of manual means for connecting one end of said spring to the motor to start the same, spring actuated means tending to connect said motor and the other end of said spring to rewind the same under the action of the motor, means controlled by the rewinding of the power spring for per-

mitting said spring actuated means to act and means controlled by said manual means for preventing said action when the other end of the power spring is connected to said motor to deliver power to the same. 25

34. In a spring starting device for an internal combustion motor, the combination with a helical spring for delivering power to the motor, of manual means for connecting one end of said spring to the motor to start the same and means brought into action as the motor starts to disconnect the spring and motor. 30
